UNITED STATES PATENT OFFICE.

JAMES T. JOHNSON, OF TENINO, WASHINGTON.

SHEAVE-BLOCK.

984,141.

Specification of Letters Patent. Patented Feb. 14, 1911.

Application filed April 12, 1910. Serial No. 555,078.

To all whom it may concern:

Be it known that I, JAMES T. JOHNSON, a citizen of the United States, residing at Tenino, in the county of Thurston and State of Washington, have invented certain new and useful Improvements in Sheave-Blocks; and I do hereby declare the following to be a full, clear, and exact description of the invention, such as will enable others skilled in the art to which it appertains to make and use the same.

My invention relates to new and useful improvements in sheave blocks and more particularly of that class adapted to be used for logging purposes and other places where heavy objects are being dragged or lifted by means of a cable and my object is to provide a two-part casing and form a hub upon one casing adapted to project through the opposite casing.

A further object is to provide means for locking the casings together.

A further object is to provide an oil chamber within the hub.

A further object is to provide a sheave and position the same between the parts of the casing, and;

A further object is to provide means for bringing the parts of the casing together at the point of greatest strain.

Other objects and advantages will be hereinafter referred to and more particularly pointed out in the specification and claims.

In the accompanying drawings which are made a part of this application, Figure 1 is a side elevation of the sheave block in its assembled position. Fig. 2 is a sectional view thereof as seen on line 2—2 Fig. 1. Fig. 3 is a side elevation of the sheave showing the parts of the casing separated to receive the cable between the sections of the casing, and, Fig. 4 is a side elevation of a slightly modified form of casing.

Referring to the drawings in which similar reference numerals designate corresponding parts throughout the several views, 1 and 2 indicate the two sections of the casing, which sections terminate at one point in ears 3 and 4, which ears are provided with alining openings 5, through which any suitable form of anchoring means may be applied. The bodies of the sections 1 and 2 are substantially circular in general outline to conform to the periphery of a sheave 6, which is adapted to fit between the sections of the casing. The ears 3 and 4 are adapted to rest against each

other when the casing is in its assembled position, while between the ears and the sections are provided curved portions 7 and 8, which when brought into registration with each other form a socket 9, through which a cable passes when coöperating with the sheave.

The casing 1 is provided with a hub 10, which extends laterally from said section 65 and passes through an opening in the section 2 and projects a distance beyond the section 2. That portion of the hub extending through the section 2 is preferably reduced in diameter to form a shoulder 11, against 70 which the section 2 abuts, thereby limiting the inward movement of said section and the section 2 is held in position on the hub by providing threads 12 on the periphery of the extended end of the hub, with which engage threads on the interior of a cap 13 and when said cap is turned on to the hub, the inner end thereof forms a jam nut for the section 2 to hold said section in firm engagement with the shoulder. The interior of 80 the hub 10 is provided with a cavity 14, in which a lubricant is to be placed, the hub having ports 15 therethrough, whereby the lubricant may pass to the wearing surface of the hub.

The cap 13 is locked in position on the hub 10 by means of a screw 16, which screw extends through the flange of the cap and entirely through the wall of the hub, so that by removing the screw 16, fluid lubricant can be introduced into the cavity without removing the cap, while the screw serves to hold the cap securely locked in position on the hub.

If desired, bearing rollers 17 may be introduced between the hub and the sheave, or if preferred, bearing balls may be used, thereby reducing the friction between the sheave and the hub.

In introducing the rope or cable into engagement with the groove 18 in the sheave, the ears 3 and 4 are swung in opposite directions until they are separated, as shown in Fig. 3, when the cable can be readily introduced into engagement with the sheave and the two ears again brought into registration with each other. This operation will result in closing that portion of the cable located between the sheave and the ears, so that it will be impossible for the cable to become entangled or run off of the sheave and it will further be seen that by arranging the

ears in this manner, the usual form of hooks, clevises and the like for anchoring the sheave block will be dispensed with. It will likewise be seen that by anchoring the sheave block by means of the ears, the walls of the casing will not be sprung inwardly to cause the same to bind upon the sheave, as is common in blocks anchored by clevises, rings and the like.

10 In Fig. 4 of the drawings, the casing is provided with a pair of ears 19 and 20, which are spaced a distance apart and arranged to receive an anchoring cable 21, which anchoring cable extends around a post 22 or other suitable anchoring means. This form of casing is primarily adapted for logging purposes and when so used, the sheave block is anchored to a stump or tree or other suitable object and it will be readily seen that by 15 spacing the ears apart, as shown, it will be impossible for the anchoring cable to become twisted, which would result in fouling the cable with the sheave when the cable is slack. This manner of anchoring the block will 20 always result in positioning the block right side up when a pull is made on the cable.

It will thus be seen that I have provided a very strong and durable form of sheave block and one that can be cheaply constructed and readily assembled together. It will further be seen that by anchoring the sheave block in the manner shown, the major portion of the strain thereon will result at the strongest portion of the block. It will likewise be seen that the block will be held against twisting action when properly anchored and especially so where the block is provided with two sets of ears. It will further be seen that by engaging the cap 30 with the end of the hub and forming the hub integral with one section of the casing, the parts of the block will be securely held in their assembled positions and it will likewise be seen that by forming the hub hollow and 35 providing the ports through the walls thereof, the wearing parts of the sheave will be thoroughly lubricated at all times by placing a lubricant in the hub. It will further be seen that the cable or rope can be quickly 40 engaged with the sheave block even though 50 both ends of the cable be attached to an object.

What I claim is:—

1. In a sheave block, a two-part casing, means to retain said parts in spaced relation to one another and a sheave mounted therebetween, said casing having the faces bulged

at the upper portions thereof to form a socket and brought into registration with one another.

2. In a sheave block, the combination with a casing formed in two sections, one of said sections having an integral hub thereon and the opposite section having an opening to receive the hub, said hub being hollow and having a shoulder, against which the section surrounding the hub rests, a cap adapted to fit over the open end of the hub, a screw extending through the cap and hub to lock the cap in position, a sheave rotatably mounted on the hub and between the sections, said sections having curved portions to form a socket, said curved portions terminating in ears, through which are formed openings to receive an anchoring means.

3. In a sheave block, the combination with a casing formed of two sections, one section having an integral hub, over the end of which is adapted to take the opposite section, said hub having a cavity therein and ports through the wall of the hub, a cap threaded on to the end of said hub, a screw extending through the cap and hub to lock the cap in position, the edges of said sections having curved portions to form a socket 85 when the sections are brought together, said curved portions terminating in registering ears, a sheave rotatably mounted on said hub and between said sections and bearing rollers between the sheave and hub.

4. A sheave block, comprising a two-part casing, the parts being held in spaced relation with one another and a sheave mounted therebetween, the faces of said casing being bulged outwardly adjacent the upper portions thereof to form a socket, said bulged portions terminating in ears adapted to register with one another for anchoring purposes.

5. A sheave block, comprising a two-part 105 casing, means to hold the parts in spaced relation with one another, a sheave mounted therebetween, the faces of said casing being bulged outwardly adjacent their upper ends, said bulged portions cooperating with said 105 sheave to form a socket for a cable, and means to anchor said block.

In testimony whereof I have signed my name to this specification in the presence of two subscribing witnesses.

JAMES T. JOHNSON.
